UNITED STATES PATENT OFFICE.

FERDINAND E. CANDA, OF NEW YORK, N. Y.

REFRIGERATOR-CAR.

SPECIFICATION forming part of Letters Patent No. 522,105, dated June 26, 1894.

Application filed January 18, 1893. Serial No. 458,805. (No model.)

To all whom it may concern:

Be it known that I, FERDINAND E. CANDA, of New York, in the county and State of New York, have invented certain new and useful 5 Improvements in Refrigerator-Cars, of which the following is a full, clear, and exact description.

The object of the invention is to provide certain new and useful improvements in refrigeration cars, whereby a maximum carrying capacity with a minimum of dead weight is obtained, the insulated condition is maintained for an indefinite period, and fresh meats, fruits and other perishable articles 15 may be safely transported for long distances with an economical consumption of ice.

The invention consists of a combination of central and outer braces with insulating linings secured to the said braces and adapted 20 to form three independent air-tight chambers, as will be fully described hereinafter and then pointed out in the claims.

Reference is to be had to the accompanying drawings, forming a part of this specification, 25 in which similar letters of reference indicate corresponding parts in all the figures.

Figure 1 is a side elevation of the improvement with parts broken out and parts in section. Fig. 2 is an enlarged transverse section of part of the improvement on the line 2-2 of Fig. 1. Fig. 3 is an enlarged sectional side elevation of a corner angle block. Fig. 4 is a plan view of the same. Fig. 5 is an enlarged sectional side elevation of a regular angle block. Fig. 6 is a plan view of the same. Fig. 7 is an enlarged transverse section of the upper part of the car body. Fig. 8 is a sectional plan view of a corner of the car body; and Fig. 9 is an enlarged sectional side elevation of part of the improvement.

The weights of various refrigerator cars in service range from twenty-five to thirty tons, and they have a capacity of from ten to twelve tons only, which shows that the relation which 45 the load bears to the dead load is totally out of proportion; that is, the cars are too heavy for the loads they carry.

Cars, as heretofore constructed, when new or recently made, are all fairly economical in 50 the use of ice, thus indicating, for the time, good insulation, and while in this condition,

they fully answer the purpose for which they are designed; but when these cars are strained from over-loading, or otherwise lose their camber or change their normal form, the insulation of such cars is greatly impaired; the paper forming an important part of the insulation is found to be torn and the other insulating materials are displaced and opening seams are formed for the warm air to gain access to the interior of the car and for the cold air from the interior of the car to escape. It follows that the usefulness of such a car is materially impaired and that thereafter its consumption of ice will be materially increased, thus rendering the running expenses very high.

In cars as heretofore constructed but little, if any, attention has been given to the proper trussing or framing of the car and ordinarily 70 too much reliance for strength has been placed in the lining, insulating divisions, and weather boards to aid in carrying the load and maintaining the form of the car, while the interior framing, if any, consists of but single posts 75 or braces with tie rods such as are used in the framing of ordinary box cars. In case ordinary box cars receive shocks their general usefulness is not apparently prejudiced, but the slightest strain or shock on a refrigerator car greatly impairs its usefulness.

In refrigerator cars of recent construction no effort has been made to reduce the dead weight of the car above mentioned, by a proper distribution of materials with reference 85 to the strains which may exist or in accord with the efficacy of the insulating materials employed, but on the contrary it appears that thick and heavy materials are considered essential to secure good results in 90 strength and insulation.

With my improvements presently to be described in detail, I overcome the above-mentioned objections and provide a car in which I secure a maximum carrying capacity with 95 a minimum of dead weight, so that the car will indefinitely maintain its insulated condition for safely transporting its contents for long distances with an economical consumption of ice.

The car body A is provided with the usual sills B and plates C connected with each other

at the corners by the usual posts D. Between the sills B and plates C, I arrange a system of trusses E which divide the body into panels through which the strains are distributed, 5 the said strains being occasioned by the car body's own weight and that of the load to be transmitted to the body bolsters of the car and thus to the trucks. Each of the trusses is composed of outer braces F, F' and central braces G resting at their lower ends on the angle blocks H and at their upper ends on angle blocks H', the said angle blocks H' being arranged vertically above the angle blocks H, the latter being held on the sill B 15 and the former on the under side of the plate C. The corresponding angle blocks H and H' are secured in place on the sill B and plate C by a vertically disposed truss rod I passing through the sill and plate and secured there- 20 to by nuts screwing on the lower and upper ends of the rod, as is plainly shown in Fig. 1.

The outer braces F, F' are arranged in pairs with the corresponding central braces passing between the outer braces F and F', 25 the braces being connected with each other at their point of intersection by a bolt J, and the ends of the outer braces F, F' being connected with each other by a bolt J', as is plainly indicated in Figs. 1 and 2. The angle blocks H and H' act as footings for the braces, the latter forming composite posts which render the car very strong and durable. 30

Each of the regular angle blocks H or H' is formed with a V-shaped bottom H² adapted 35 to receive, on each side, the beveled end of the angularly-arranged braces F, F' or G, see details in Figs. 5 and 6. In order to separate the outer braces F and the corresponding central braces G, I provide the bottom H² with 40 longitudinally-extending flanges H³, on the outside of which fit the outer braces, while between the flanges passes the lower end of the central brace. From the center of the angle block extends downward a hub H⁴ adapted to 45 engage a corresponding recess formed in the respective sill B or the plate C, and through this hub also passes the vertically disposed truss rod I, as is plainly illustrated in Fig. 2. The V-shaped bottom H² is provided on its 50 under side with longitudinally-extending loops H⁵ adapted to rest with their straight edges on the surface of the respective sill B or plate C. The angle blocks for the corners of the car are formed with a horizontal ex- 55 tension H⁶ recessed for the reception of the corner post D, as will be readily understood by reference to Figs. 1, 3 and 4. As only one set of outer braces and central braces extends to such corner angle block, the latter is pro- 60 vided with a single inclined bottom, as is plainly shown in Figs. 3 and 4.

A light lining K of wood is placed between the adjacent surfaces of the front outer braces F and central braces G, and a like lining K' 65 is arranged between the adjacent faces of the central braces G and the outer main braces F', see Figs. 7 and 8. The linings K and K'

are covered on their outer surfaces by an insulating paper L, L' respectively. Against the outer faces of the outer braces F I arrange another lining N, of wood, and a similar lining N' covers the inner face of the outer braces F', this lining also forming the inner wall of the car body A. A paper O is arranged on the inner surface of the lining N, 70 and a similar paper O' is arranged on the inner surface of the lining N', so that the outer braces F are placed between the papers O and L, and the outer braces F' between the papers L' and O'. By this arrangement three independent air spaces or chambers P, P' and P² are formed in each side of the car, the braces F, F' and G extending through the said spaces. The spaces P, P', P² may be filled with any 80 of the well known insulating materials, such as air, felt, woolen rags, granulated cork, &c. The inner lining N' is formed of boards having longitudinally-extending grooves N², which grooves are placed outward when the bolts are put in position, so as to form, with the paper O', longitudinally-extending air spaces, at the same time reducing the weight of this lining by having the material cutaway to form the grooves N². 85

The weather boards Q attached vertically 90 to the rails R, in the usual manner, are formed with grooves Q' similar to the grooves N², which are placed inward to form vertically-disposed air channels extending between the lining N and the weather boards. The inner 95 faces of the weather boards Q are a suitable distance from the outer face of the lining N, so that a fourth space P³ is formed, the said weather boards forming an outer jacket for the car body, with a free air space, thus facilitating the exit of the heat due to radiation, which heat can thus be carried off through the flues in the weather boards as it ascends, discharging itself near the top of the car into a chamber Q² located immediately under the 100 inner roof boards S. From the chamber Q² extends downward on the outside of the weather boards Q a short channel Q³, situated under the facia boards Q⁴, and opening to the outside to permit the air ascending the 105 grooves Q', to the chamber Q² to pass out to the outer air. The interior roof boards S are covered by a metallic lining T, so that any leakage of water from the exterior roof V can pass down said metallic lining to the side of 110 the car to drip through a vertically-disposed channel U between the facia boards V² and Q⁴, to the ground. The exterior roof V is located a suitable distance above the lining T and is supported on longitudinal stringers 115 or purlins, V', which rest on the ribs T', as is plainly shown in Figs. 7 and 9. Each outer end of the said roof boards V supports downwardly-extending facia boards V² forming the exterior covering of the channel U. 120 Each rib T' is covered by a metallic cap T² see Fig. 9, approximately U-shaped in cross section, and extending over the upturned ends of the metallic lining T, which has its edges 125

embedded in longitudinal recesses formed in the sides of the respective ribs T', as will be readily understood by reference to Fig. 9.

As illustrated in Fig. 2, the floor W of the car is formed with dead air spaces W', and the ceiling W² of the car is likewise formed with dead air spaces W³, the several partitions being lined with paper on top, as is plainly shown in Fig. 7. The lining boards W⁴ for the ceiling are similar in construction to the interior lining N' arranged on the sides and ends; that is, they are provided with longitudinally extending grooves forming dead air spaces by being covered with paper, as will be readily understood by reference to Fig. 7.

It will be seen that by the construction referred to I can proportion the framing of the car to meet the requirements of strength without the use of unnecessary materials, causing dead weight; and that the covering of the car, as well as the materials required for insulation can be exceptionally light, as no reliance whatever is placed on these parts to support the load.

A special advantage of the improved car is the arrangement of a central insulating chamber inclosed between two outer insulating chambers, each of the chambers being separate and independent from the others. It will be observed that the insulating partitions are comparatively light and the usual practice of furring which considerably increases the weight of the car, is avoided.

It will further be seen that by this system of trussing above described I am enabled to distribute the materials in the various members according to the strains which may occur, and thereby save much otherwise unnecessary weight.

The braces F F' and G respectively constitute a very strong framing for the car, the function of the outer braces being to receive and distribute the load throughout the car and carry it from its center and end to the body bolster, while the central braces practically do not receive or distribute any part of the load but serve in other very essential points in the framing of a refrigerator car, namely: They represent an absent load in the car and make it possible for the car to resist shocks in a train which without them would have the effect of raising the center of the car above its normal position thereby tearing the insulating paper or displacing the insulating material, and thus impairing the future service of the car. The central braces also take the place of furring strips which would otherwise be necessary and in connection with the outer braces form the required insulating chambers or divisions between which the inner linings extend the full length from the end of the car to the door posts,

thereby adding strength to the construction. It will be seen from the foregoing that the braces have fixed duties to perform which could not be accomplished by any other system of trussing without the use of much unnecessary material and consequent addition of weight and cost of structure.

A car constructed in the manner described will have a weight corresponding about to that of the carrying capacity, at the same time preventing the destruction of the insulation.

I have described a system of trussing with outer and counter braces, the central brace occupying a space between the two outer braces, and this method I prefer to employ in practice.

Having thus fully described my invention, I claim as new and desire to secure by Letters Patent—

1. In a refrigerator car, the combination, with the central braces, of insulating linings placed on each side thereof, and braces arranged outside of each of said insulating linings, substantially as herein shown and described, whereby a central independent insulating chamber is formed between said outer braces, as set forth.

2. In a refrigerator car, the combination, with the central braces, of insulating linings placed on each side thereof, forming an interior central independent insulating chamber, outer braces arranged outside of said insulating linings, and insulating linings secured upon the outer surfaces of said outer braces, substantially as shown and described, whereby the said interior insulating chamber is inclosed between two exterior insulating chambers, as set forth.

3. In a refrigerator car, the combination of the following instrumentalities, namely, a frame consisting of inner and outer braces with their adjuncts, insulating linings arranged upon the sides of the inner braces, thereby forming an independent central insulating chamber inclosing the central braces, and insulating linings secured upon the exterior sides of the outer braces, thereby forming two separate independent exterior insulating chambers which inclose the central insulating chamber and also inclose the exterior braces, as herein set forth.

4. A refrigerator car provided with weather boards having vertically-disposed grooves forming air channels, the lower ends of which open to the outside and the upper ends into an air chamber formed in the roof, the said chamber being connected by a downward channel with the outside air, substantially as shown and described.

FERDINAND E. CANDA.
